Fig. 1.

Fig. 2.

Fig. 3.

The characteristic feature of my design resides in the configuration of the combination of the top bottle and closure cap portion as shown applied to the bottom bottle on the drawing.

What I claim is:

The ornamental design for a combination bottles and cap portions therefor, substantially as shown and described.
